UNITED STATES PATENT OFFICE.

ROBERT H. STRONG, OF GALESBURG, ILLINOIS, ASSIGNOR OF TWO-THIRDS
TO WILLIAM O. R. BRADLEY AND JOHN P. MCCAFFERY, OF GALESBURG,
ILLINOIS.

MACHINE FOR AFFIXING POSTAGE-STAMPS OR LABELS UPON ENVELOPS, CARDS, &c.

SPECIFICATION forming part of Letters Patent No. 708,423, dated September 2, 1902.

Application filed April 1, 1902. Serial No. 100,924. (No model.)

To all whom it may concern:

Be it known that I, ROBERT H. STRONG, a citizen of the United States, residing at Galesburg, in the county of Knox and State of Illinois, have invented certain new and useful Improvements in Machines for Affixing Postage-Stamps or Labels upon Envelops, Cards, &c., of which the following is a specification.

This invention relates to certain new and useful improvements in machines the function of which is to separate and affix stamps or labels having an adhesive surface to envelops, cards, or other objects; and the invention consists in the construction and combination of the parts which constitute such a machine, as will be hereinafter set forth.

The object of the invention is to provide a device in which a sheet with adhesive material on one side may be carried beneath cutters which when operated will sever a rectangular portion from the sheet and press such severed part upon an envelop or other surface which has been moistened to attach the stamp or label thereto.

In the accompanying drawings, Figure 1 is a plan view of an envelop-moistener and a stamp or label affixer constructed in accord with the invention. Fig. 2 is a front elevation. Fig. 3 is a vertical sectional view on the line 2-2 of Fig. 2. Fig. 4 is a detail perspective view showing the pivoted cutters, and Fig. 5 is a perspective view of the stop and release mechanism for the carriage.

Upon a suitably-constructed base A are mounted supports *a a*, which carry a rod *a'*, a carriage *A'* being pivotally attached to the rod, so as to slide thereon. The carriage is drawn toward one end of the base by a flexible connection *b*, which is attached to one end of the carriage, the other end being wound about a spring-drum *b'*, which may be rotatively mounted on a bracket or upright *b''*. The carriage *A'* has near its front lower edge a feed-roller *a''*, a rod passing through such roller and being journaled in the end pieces of the carriage, the rod provided beyond one of the side pieces of the carriage with a knob for turning the feed-roller, and the roller may be provided with rings *a'''* to frictionally en-

gage the sheet which is placed between the front and back plates of the carriage. The length of the carriage may be such that it will receive between its ends a sheet which is equal in length to the length of ten postage-stamps, the distance between the end plates of the carriage may be less, and the movement of the carriage is step by step and equals the length of a label or stamp which it is desired to affix. The step-by-step movement of the carriage is governed by the distance between the vertical members or teeth of a rack-bar *A''*, which is attached to the carriage and depends from the central portion of the back plate thereof. From the back plate of the carriage *A* project lugs *A''*, through which the rod *a'* passes, and the carriage is pivoted to this rod and is in sliding engagement therewith, and as the carriage may be tilted on its pivot the rack-bar, which is rigidly attached to the carriage, will be moved therewith and when the carriage is raised will be positioned to one side of the stop and release mechanism. The carriage is reciprocated or moved by a spring and flexible connection over a plate *B*, which is attached to the base and supported so as to be slightly above the plane or upper surface of the base to provide a recess beneath which envelops or other objects may be passed in order to have stamps or labels affixed thereto. The plate *B* is cut away to provide a space for pivoted knives, and the plate adjacent to the knives has strips *b'*, against which the pivoted members of the cutters bear when depressed. The plate *B* also carries a guide *b''*, beneath which the stamps or labels pass to properly guide them to the cutters.

The stop and release mechanism is supported by an angular plate *C*, attached to the base, and this plate carries an angular or inclined piece *C'*, which provides a stop to limit the rearward movement of a dog *D*, which is pivoted to the vertical portion of the plate *C*, so that its rearwardly-projecting upper end may abut against the stop-plate *C'*. The oscillating member or dog *D* to one side of its pivot *d'* carries a spring *d''*, which abuts against a depending member *e* of an oscillat-

ing pawl E, which is pivoted to the dog D. This part E overlies the part D and is normally thrown toward the rearwardly-projecting upper member thereof by the spring d^2 , 5 and one of the sides extends sufficiently to be engaged by the vertical members of the rack-bar. Said bar as drawn toward one end of the base by the spring-actuated drum causes one of the vertical members of the teeth of 10 the rack to engage one side of the pawl E, which effects a stoppage of the carriage. A downward pressure being exerted on the rod F rocks the dog and moves its end d away from the stop-plate, and at the same time the 15 rack-bar slides over the side of the pawl and engages the side of the dog. On the movement of the dog D toward the stop-plate, which takes place when the rod is allowed to move upward, the rack-bar will engage the edge e' 20 of the pawl, move it against the action of its spring d^2 , at the same time sliding over the side of the dog until it passes beyond its edge, when the rack-bar and carriage will advance one step, the next tooth of the rack-bar en- 25 gaging the side of the pawl, which is immediately thrown in the path of the rack-bar by the spring d^2 . The dog is rocked toward the front of the machine by a downpull on the rod F, which is connected to the dog and to 30 the bar G, which bar is moved upward by a spring h'. When the rearward-projecting upper end of the dog is against the stop-plate C', the part E will be engaged on one side by a vertical member of the rack-bar, and when 35 the rod is drawn upon the dog and the part E will be swung toward the front the vertical member which engages with the side of the part E will slide on said part and contact with the upper portion of the dog. As the rod F 40 is allowed to move upward the rearwardly-projecting upper end of the dog will move toward the stop-plate, and the part E will by being in engagement with the rack-bar be swung on its pivot, the parts being separated 45 to provide a space through which the rack-bar may pass, such operation being repeated as often as the rod F is depressed and released. The upper end of the pawl E is beveled, so that when the carriage is moved against the 50 action imparted thereto by the spring-actuated drum the rack-bar will engage the beveled end and permit the carriage to be moved past the pawl when said carriage slides on its bar and its front edge on the plate B. By 55 lifting the front edge of the carriage the rack-bar can be moved entirely out of the path of the stop and release mechanism.

G refers to a bar which is pivoted to the rear edge of the base and extends beyond the 60 front thereof, and this bar or lever has a block g, so that it may be readily depressed by hand, though in practice to the front end of the lever is attached a rod g', which extends downward and connects with a treadle 65 of ordinary construction. The rod F is connected to the lever G near its pivot, and at a suitable point through the base, so as to en-

gage with the lever, is a connecting-rod h, which has a spring h', the spring being between the base A and the under side of a 70 pivoted plate I, which serves as a presser and cutter. The bolt above the presser and cutter I is threaded and carries a nut i.

A blade or cutter J is pivoted to a vertical portion which projects from a strip b', and this blade has therethrough an aperture k, the end of the blade being beveled to correspond with the beveled projecting corner k' of the blade and presser I, so that the ends of the pivoted cutters will fit snugly against 80 the strips b'. To the blade and presser I there is attached a bar I², the free end being passed through an aperture k in the blade J, so that when the presser and cutter is raised the blade J will be raised in unison therewith. To the base there is attached an upright L, which carries a horizontal pin or bar m, and on the same is pivoted a frame m', to which is attached, so as to have a limited range of oscillatory movement, a pad-carrying 90 frame N, the pad which is carried thereby being adapted to enter a depression or water-containing recess O in the base. The pad-carrying frame is normally forced into the recess by a spring n, which is carried by the 95 rod, one end of the spring bearing on the frame or yoke m', to which the pad-carrying frame is pivoted.

P refers to a water-tank which is suitably attached to the base and has pipes or connections which lead to a tube P', located immediately above the pad which is carried by the frame N, and the end of this tube P' may have a cap either to cut off entirely the flow from the water-tank or to regulate the drip. 105

In operation a sheet of postage-stamps is placed in the carriage the lower edges being passed beneath the roller a², the carriage is drawn to one end of the base away from the pivoted knives, the moistening-pad is wet by 110 water from the supply-tank. When the roller is turned by the knob, the sheet will be fed under the guide-plate b². The machine is now ready for operation. An envelop is passed under the moistener, one corner lying 115 beneath the presser and cutter, the lever G is depressed, such movement operating the stop and release mechanism, which allows the carriage to travel one step, which places the corner of the sheet beneath the presser 120 and cutter, the next action being to lower the pivoted blades, which will sever the stamp or label from the sheet and press the severed portion against the moistened corner of the envelop. The envelop is then withdrawn, another one inserted, and the operation repeated until the entire lower strip has 125 been removed, after which the carriage is restored to its initial position and the roller is turned to feed another strip in line with the 130 cutters.

I claim—

1. In a machine for the purpose set forth, a base having thereon a water-supply tank, a

moistener below the end of a pipe connected with the water-tank, a reciprocating carriage which travels in the rear of the moistener, two cutters each pivotally mounted at right angles to the other, and a plate which provides a space open on two sides, substantially as shown.

2. In a machine for the purpose set forth, the combination with a plate having an opening to receive an envelop, a moistening device constructed to contact with a part of the envelop in its passage beneath the plate to moisten such part of the envelop, a blade coacting with one edge of the plate and a blade 15 coacting with the other edge and with the first-mentioned blade, the blades being relatively movable with respect to each other to sever a piece from a sheet, one of the blades having a flat portion of sufficient width to 20 cover the severed portion of the sheet, for the purpose set forth.

3. In a machine for clipping and affixing rectangular pieces from a gummed sheet, the combination with a pivoted and upwardly-25 movable moistening-pad, fixed lower cutters and movable upper cutters arranged in line therewith and at right angles to each other, a carriage carrying a gummed sheet, means for moving the carriage step by step and means 30 for depressing the upper cutters, substantially as shown.

4. In a machine for the purpose set forth, a carriage having a rack-bar rigidly attached thereto, a rod for supporting the carriage said 35 carriage being in swinging and in sliding engagement therewith, a stop and clutch mechanism for engagement with the rack-bar, comprising a pivotally-supported dog, a pawl which overlies one side of the dog and the end 40 thereof, the overlying side of the pawl arranged to engage the teeth of the ratchet-plate, substantially as set forth.

5. In a machine for the purpose set forth, the combination of a reciprocating carriage, 45 a supporting-rod therefor, a stop and release

mechanism comprising a fixed ratchet-plate which moves in unison with the carriage, a pawl with which the vertical members of the teeth of the ratchet-plate engage, a dog also engaged by the same portion of the ratchet-50 teeth, means for swinging the dog and the pawl when the latter is engaged by the ratchet-plate to provide a space between the dog and pawl for the passage of one tooth of the ratchet-plate, a spring-drum, a flexible connection between the drum and the carriage, a lever with which the stop and release mechanism is connected, a pivoted bar connected to the dog, fixed lower cutter and movable upper cutters carried by the base, the upper 60 cutters being in movable engagement one with the other, and a rod connecting one of the upper cutters with the pivoted bar to operate the upper cutters when the bar is depressed, substantially as shown. 65

6. In a device for the purpose set forth, the combination of a base, a carriage-supporting frame attached to the base, a carriage movable on the frame, a ratchet-plate attached to the carriage, a spring-actuated drum mounted on the base, a flexible connection attached to the drum and to the carriage, a lever pivoted to the under side of the base, a stop and release mechanism actuated by the lever for engagement with the ratchet-plate, a pair of 70 pivoted cutters arranged at right angles to each other, a spring for lifting one of the cutters, fixed lower cutters which coöperate with the pivoted cutters, means for connecting one of the blades to the lever, means carried by said blade for engagement with the pivoted blade at right angles thereto, and a moistener in proximity to the cutting-blades, 75 substantially as shown.

In testimony whereof I subscribe my name 80 in the presence of two witnesses.
